US0D1100470S

(12) **United States Design Patent** (10) **Patent No.:** **US D1,100,470 S**
(45) **Date of Patent:** ** *Nov. 4, 2025

(54) **FOOTWEAR**

(71) Applicant: **SALOMON S.A.S.**, Epagny Metz-Tessy (FR)

(72) Inventor: **Nicolas Diacre**, Annecy (FR)

(73) Assignee: **Salomon S.A.S.**, Epagny Metz-Tessy (FR)

(*) Notice: This patent is subject to a terminal disclaimer.

(**) Term: **15 Years**

(21) Appl. No.: **29/884,169**

(22) Filed: **Feb. 8, 2023**

(30) **Foreign Application Priority Data**

Oct. 7, 2022 (WO) WIPO123480

(51) LOC (15) Cl. **02-04**

(52) U.S. Cl.

USPC **D2/972**

(57) **CLAIM**

The ornamental design for a footwear, as shown and described.

DESCRIPTION

FIG. 1 is a front, first side perspective view of a footwear showing my new design;

FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The evenly dashed broken lines shown in FIGS. 1-7 are included for the purpose of illustrating portions of the footwear that form no part of the claimed design.

1 Claim, 6 Drawing Sheets
